PAGE 2

Fig. 3

Fig. 5

FIG. 1 is a top plan view of a swimming pool enclosure showing my new design;

FIG. 2 is a front elevational view thereof;

FIG. 3 is a rear elevational view thereof;

FIG. 4 is a right side elevational view thereof; and

FIG. 5 is a left side elevational view thereof; and

FIG. 6 is an enlarged fragmentary perspective view thereof showing the interior of the front right hand corner.

I claim:

The ornamental design for a swimming pool enclosure, as shown.
